UNITED STATES PATENT OFFICE.

ARTHUR E. ANAKIN, OF LONG BEACH, CALIFORNIA.

AUXILIARY SAFE LOCK.

Application filed July 5, 1922. Serial No. 572,935.

To all whom it may concern:

Be it known that I, ARTHUR E. ANAKIN, a citizen of the United States, residing at Long Beach, in the county of Los Angeles and State of California, have invented new and useful Improvements in Auxiliary Safe Locks, of which the following is a specification.

My invention relates to vault and safe locks, and more particularly to an auxiliary lock for safes of that character which are normally maintained in a non-locking position but which are adapted to be automatically moved to locking position when the primary lock is burnt or blown out, thereby securely locking the safe door against opening.

It is the purpose of my invention to provide an auxiliary safe lock of the above described character which is of extremely simple, durable and efficient construction and which eliminates the use of springs or other elements which in due time lose their resilient properties, so that they no longer function.

It is also a purpose of my invention to provide an auxiliary safe lock which operates in such a manner as to prevent the possibility of the lock being unintentionally moved into locking position, certain portions of the lock being adjustable to vary the force necessary to move the lock to locking position, so that when once set to accord with the particular conditions, it can be moved to locking position only when the primary lock of the safe is removed.

Although I will describe only one form of auxiliary safe lock embodying my invention and point out the novel features thereof, in claims, it is to be understood that various changes and modifications may be made herein without departing from the spirit of the invention and spirit and scope of the claims.

In the accompanying drawings,

Figure 1 is a view showing a conventional form of safe having applied to the door thereof one form of auxiliary lock embodying my invention;

Figure 2 is a fragmentary sectional view of a portion of the safe shown in Figure 1 with the door in closed position and the lock in locking position;

Figure 3 is a detail view showing in ver-

tical section the lock shown in the preceding views;

Figure 4 is a bottom plan view of the lock shown in Figure 3;

Figure 5 is a fragmentary view partly in section showing a modified form of auxiliary lock embodying my invention.

Referring specifically to the drawings, in which similar reference characters refer to similar parts, my invention in its present embodiment comprises a metal sleeve 15 closed at its lower end, as indicated at 16, and having a reduced upper end to provide an annular shoulder 17. The upper end of the sleeve is beveled, as indicated at 18, to facilitate the outward flaring of this end when the sleeve is in applied position within a door. A collar 19 is secured to the lower end of the sleeve 15 by means of a set screw 20, and this collar is adapted to support a bolt projecting member, designated generally at 21. The bolt projecting member, in the present instance, comprises a lever including a relatively long arm 22 and a short arm 23 connected by a vertical portion 24.

As clearly shown in Figure 4, the collar 19 is provided with spaced ears 25 and extended through these ears is a bolt 26 carrying a nut 27 and a lock washer 28. This bolt 26 provides a pivot for the bolt projecting member 21, and as shown the bolt is extended through a suitable opening formed in the vertical portion 24 of the lever. With the lever so arranged, the arm 22 extends through a slot 29 formed in the sleeve 15 so as to engage the lower end of a bolt 30. This bolt 30 is slidably mounted in the sleeve 15 and is adapted to occupy a non-locking position, as shown in Figure 3, or a locking position, as shown in dash lines in Figure 3. The bolt projecting member 21 is designed to move the bolt 30 to the locking position, it being understood that normally the bolt gravitates to non-locking position. By rocking the lever from the position shown in solid lines to that shown in dotted lines in Figure 3, the bolt 30 can be raised to locking position wherein its upper end is projected from the upper end of the sleeve 15.

It will be clear that to move the lever to the dotted position it is necessary to exert a downward force upon the free end of the arm 23. The pressure necessary to operate the lever

to project the bolt depends upon the frictional contact set up between the faces of the lever and the confronting faces of the ears 25. The material of which the collar and 5 ears are formed is slightly resilient so that the ears can be compressed by a tightening of the nut 27 upon the bolt 26. Consequently the friction set up between the lever and the ears depends upon the relative positions of 10 the ears and the adjustment of the nut 27. It will, therefore, be seen that the pressure necessary to operate the lever can be varied in accordance with the adjustment of the nut 27.

15 In the applied position of the lock, as shown in Figures 1 and 2, the upper end of the sleeve is extended through a suitable opening formed in the upper wall of the safe door, a shoulder 17 abutting the inner side of 20 the wall, and the beveled edge 18 being flared outwardly so as to secure the retaining sleeve within the opening. A recess 31 is formed in the safe body so that when the door is in closed position the upper end of 25 the bolt 30 will be in registration with said recess. A flexible member 32, such as a tape, metal strap, or the like, is secured to the free end of the arm 23 and this member is of sufficient length so as to reach the primary lock 30 30 33 of the safe, its lower end being secured by a screw or other suitable fastening 34 to the lock.

With the lock so applied, it will be clear 35 that when the primary lock 33 is removed inwardly with respect to the door, the force necessary to remove the lock will act upon the flexible member 32 to operate the projecting member 21, thereby causing the latter to elevate the bolt to locking position 40 within recess 31. Because of the friction set up between the lever and the ears 25, it will be clearly seen that after the lever has been moved into the bolt ejecting position, it will remain in such position to retain the bolt in locking position within the recess so that 45 in spite of the removal of the primary lock 33 the door will be securely retained in closed position.

50 In practice, the nut 27 is so adjusted that the pull upon the flexible member 32 necessary to operate the lever will be about twenty pounds so that during the normal operation of the primary lock the swinging of the door to closed position will be ineffective to operate the lever to cause a projection of the bolt 30 into locking position. This obviously prevents the accidental operation of the lock as is now possible with similar locks heretofore proposed.

55 Referring now to Figure 5, I have here shown a modified form of auxiliary lock in which the bolt designated at 30^a is mounted in a tubular sleeve 15^a, the lower end of which is closed by a plug 35. Extended through the lower end of the plug 35, and

sleeve 15 is a pin 36. One end of the pin 36 is upset, while the other end is provided with a bifurcated extension 37, such extension being of a diameter greater than that of the pin 36 so as to provide a shoulder at the junction of the two which cooperates with the upset end for securely retaining the pin within the bolt and sleeve. The extension 37 receives the bolt projecting member in the same manner as the arms 25 in the first form 75 of lock, the bolt 26 being extended through the extension 37 and provided with a nut 27 for restricting the arms of the extension to control the movement of the bolt ejecting member.

56 I claim as my invention:

1. An auxiliary lock comprising a bolt sustained to occupy either of two extreme positions, and a member pivoted so as to be frictionally retained in any position to which it is moved, said member engaging one end of the bolt and being adapted to move said bolt from one extreme position to the other and to retain the bolt in either of said positions.

2. In combination, a safe door, a primary lock thereon, a bolt mounted for movement in the door to occupy locking and non-locking positions, a movable member mounted so as to be frictionally retained in any position to which it is moved, said member being associated with the bolt so that when actuated the bolt is moved from non-locking to locking position, and a member connected to the member and secured in spanning relation to said primary lock.

3. An auxiliary lock comprising a bolt sustained to occupy either of two extreme positions, a lever adapted to move the bolt from one extreme position to the other, and adjustable resilient means for frictionally retaining the lever and consequently the bolt in any adjusted position.

4. An auxiliary lock comprising a bolt sustained to occupy two extreme positions, a member pivoted to engage and move the bolt from one extreme position to the other, and means associated with the member for varying the force necessary to actuate the member.

5. An auxiliary lock comprising a bolt mounted to occupy two extreme positions, a lever mounted so that when actuated the bolt is moved from one extreme position to the other, a member for sustaining the lever so as to set up friction between the member and lever, and means for adjusting the member to vary the friction between the member and lever for the purpose described.

6. An auxiliary lock comprising a bolt sustained to occupy either of two extreme positions, a lever adapted to move the bolt from one extreme position to the other, spaced members of resilient material, a bolt extending through the members and said

lever for pivotally sustaining the latter, and a nut on the bolt for contracting the spaced members to vary the gripping action of the spaced members with respect to the lever.

7. An auxiliary lock comprising a bolt sustained to occupy either of two extreme positions, and a member vertically pivoted to be retained in any position to which it is moved, said member being adapted to move said bolt from one extreme position to the other.

8. An auxiliary lock comprising a slotted sleeve, a collar secured to the sleeve, spaced resilient arms formed on the collar, a locking bolt slidable in the sleeve, a lever extending into the slot of the sleeve and adapted to move the locking bolt to either of the two extreme positions, a bolt extending through the arms and lever and pivotally sustaining the latter, and means on the bolt for contracting the arms to vary the gripping action thereof with respect to the lever.

9. In combination, a safe door, a primary lock thereon, a bolt mounted for movement in the door to occupy locking and non-locking positions, a movable member mounted so as to be frictionally retained in any position to which it is moved, said member being associated with the bolt so that when actuated the bolt is moved from non-locking to locking position, and a flexible member connected to the member and secured in spanning relation to said primary lock.

10. In combination, a safe comprising a locking mechanism and a door, an auxiliary locking mechanism including a supporting member mounted on the door, and a locking bolt carried by the supporting member and normally urged to non-locking position with respect to the door, means for projecting the locking bolt to locking position with respect to the door on tampering with the main

locking mechanism, and means for frictionally retaining said means in any adjusted position whereby when the locking bolt is moved to locking position it will be retained in said position.

11. In combination, a safe comprising a locking mechanism and a door, an auxiliary locking mechanism including a supporting member mounted on the door, and a locking bolt carried by the supporting member and normally urged to non-locking position with respect to the door, means for projecting the locking bolt to locking position with respect to the door on tampering with the main locking mechanism, and for retaining said means in any adjusted position whereby when the locking bolt is moved to locking position it will be retained in said position.

12. A combination as embodied in claim 11 wherein the means for frictionally retaining said means in any adjusted position can be adjusted to vary the force necessary to actuate the means for protecting the locking bolt.

13. In combination, a safe comprising a locking mechanism and a door, an auxiliary locking mechanism including a supporting member mounted on the door, and a locking bolt carried by the supporting member and normally urged by gravity to non-locking position with respect to the door, means for projecting the locking bolt to locking position with respect to the door on tampering with the main locking mechanism, and for frictionally retaining said means in any adjusted position whereby when the locking bolt is moved to locking position it will be retained in said position.

In testimony whereof I have signed my name to this specification.

ARTHUR E. ANAKIN.
